(57) **CLAIM**

The ornamental design for the cover for wire harness connecting vehicular illuminated indicia, as shown and described.

DESCRIPTION

FIG. 1 is a top, left, rear perspective view of the cover for wire harness connecting vehicular illuminated indicia showing my design;

FIG. 2 is a bottom, right, rear perspective view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof;

FIG. 8 is a bottom plan view thereof;

FIG. 9 is a top, left, rear perspective view of the cover for wire harness connecting vehicular illuminated indicia showing my design covering a harness connecting four indicia;

FIG. 10 is a top, left, rear perspective view of the cover for wire harness connecting vehicular illuminated indicia showing my design covering a harness connecting three indicia;

FIG. 11 is a bottom, right, rear perspective view of the cover for wire harness connecting vehicular illuminated indicia showing my design attached to a wire harness connecting three indicia; and,

FIG. 12 is a top plan view of the cover for wire harness connecting vehicular illuminated indicia showing my design as attached to a portion of an emergency response vehicle depicted covering a wire harness connecting four indicia.

The broken lines shown represent environmental subject matter that forms no part of the claimed design. Specifically, the indicia and wire harness illustrated in FIGS. 9-12; and the portion of the emergency response vehicle shown in FIG. 12 illustrate environment of the cover for wire harness connecting vehicular illuminated indicia forms no part of the claimed design. Further, FIG. 12 includes two dash-dot border lines that limit the environmental subject matter depicted to that of a portion of an emergency response vehicle. The dash-dot border lines as well as portions of the environmental subject matter depicted form no part of the claimed design.
